US0D1066397S

(12) **United States Design Patent** (10) Patent No.: **US D1,066,397 S**
(45) Date of Patent: ** Mar. 11, 2025

(54) **AUTOMOBILE DISPLAY SCREEN WITH GRAPHICAL USER INTERFACE**
(71) Applicant: **Atieva, Inc.**, Newark, CA (US)
(72) Inventors: **Nicholas James Hope**, Oakland, CA (US); **Chunkwok Lee**, Campbell, CA (US)
(73) Assignee: **Atieva, Inc.**, Newark, CA (US)
(**) Term: **15 Years**
(21) Appl. No.: **29/850,122**
(22) Filed: **Aug. 17, 2022**
(51) LOC (15) Cl. **14-04**
(52) U.S. Cl. **USPC D14/486; D14/485**
(58) **Field of Classification Search**
USPC D14/489-495, 485-488

CLAIM

The ornamental design for an automobile display screen with graphical user interface, as shown and described.

DESCRIPTION

The FIGURE is a front view of an automobile display screen with graphical user interface, of the new design.

The outermost broken line rectangle shows the display screen, and forms no part of the claimed design. The masked area within the white broken lines of the graphical user interface forms no part of the claimed design.

1 Claim, 1 Drawing Sheet
